FEED-CUP PRESSURE REGULATING MECH-
ANISM FOR SEWING MACHINES

Hans Hacklander, Linden, N. J., assignor to The
Singer Manufacturing Company, Elizabeth,
N. J., a corporation of New Jersey

Application August 26, 1948, Serial No. 46,234

9 Claims. (Cl. 112—16)

1

This invention relates to sewing machines and more particularly to a sewing machine of the type having feeding wheels or "cups" for supporting and feeding the work to the stitching mechanism.

An object of the invention is to provide an improved means for adjusting the pressure between the two feed-cups, which means is readily accessible to the operator and can be manually operated without tilting the machine or removing any cover-plate.

Another object of the invention is to provide a cup-feed type of sewing machine with feed-cup pressure-adjusting mechanism which is self-locking, whereby any selected pressure between the feed-cups will be maintained.

The invention further relates to arrangements and combinations of parts which will be more fully described hereinafter, pointed out in the appended claims and illustrated in the accompanying drawings, in which:

Fig. 1 is a rear elevational view of a sewing machine embodying the invention with a portion of the back wall partly broken away to expose the components of my improved mechanism.

Fig. 2 is a vertical sectional view of the upper portion of the sewing machine looking from the right side, illustrating the manner in which the outer feed-cup is supported within the overhanging bracket of the machine-frame.

Fig. 3 represents an enlarged horizontal section taken substantially along the line 3—3, Fig. 1.

Fig. 4 represents an enlarged horizontal section taken substantially along the line 4—4, Fig. 1.

Fig. 5 is a top plan view of the machine with the cover-plate removed, showing the belt-drive and the pivotally mounted supporting lever for the outer feed-cup.

Fig. 6 is a perspective view of the supporting lever for the outer feed-cup.

Fig. 7 is an enlarged perspective view of a modified means for keying the spring-pressure adjusting disk to the pull-rod.

Referring now to the drawings, the present invention is shown as embodied in a cup-feed sewing machine similar to that forming the subject of my prior U. S. Patent No. 2,277,971, issued March 31, 1942. The machine illustrated has a machine-frame including a base-portion or standard 10 and a laterally projecting overhanging bracket 11. Formed integral with the standard 10 and disposed beneath the overhanging bracket 11 is a supporting lug 12 (Fig. 2) sustaining the inner feed-cup 13 of the feeding mechanism. Cooperating with the inner feed-cup 13 is an outer feed-cup 14 which depends from the overhanging bracket 11, the two feed-cups cooperating to support and feed fabric sec-

2

tions past the stitch-forming devices at a uniform rate. Removably secured on the top of the overhanging bracket 11 is a cover-plate 15 which is fastened by means of a screw 16.

The standard 10 of the machine-frame is formed adjacent its top with a horizontal partition 17 which divides the machine-frame into a splash-lubrication compartment 18 and a belt-compartment 19 in the overhanging bracket 11. The splash-lubrication compartment is closed at the bottom by means of a removable plate 20 secured by screws 21 and sealed by a gasket 22.

Disposed in the splash-lubrication compartment 18 transversely of the machine-frame is a rotary main-shaft 23 journaled at opposite ends in bushings 24 and 25 fixed in the side walls of the standard 10. Mounted on the opposite ends of the main-shaft 23 are the usual balance-wheels 26, each having preferably a V-shaped belt-groove 27. Within the splash lubrication compartment, the main-shaft 23 is provided with suitable cranks and eccentrics for actuating the stitch-forming devices and the feeding mechanism. A complete disclosure of the arrangement of the cranks and eccentrics, together with the actuating mechanisms for the stitch-forming devices and the feeding cups can be had in my previously mentioned U. S. Patent No. 2,277,971.

The stitch-forming mechanism of the illustrated machine includes a needle 28 and a looper 29 (Fig. 2). Co-operating with the needle and looper is a spreader (not shown). The needle 28 is carried in a needle-bar 30 journaled for endwise reciprocation in spaced bearings 31 and 32 provided in the machine-frame. The looper 29 is carried by a rock-shaft 33 journaled in a bushing 34 penetrating the front wall of the standard 10. Within the splash-lubrication compartment 18, the needle-bar 30 and the looper rock-shaft 33 are adapted to be operatively connected to the main-shaft 23.

As previously mentioned, the work to be stitched is fed past the stitch-forming devices by the two feed-cups 13 and 14, both of which are driven by connections operated by the main-shaft 23. The connections used are similar to those fully disclosed in my previously mentioned Patent No. 2,277,971. Included in the feed-cup actuating connections is a vertically disposed feed-actuating shaft 35 connected at its lower end, within the standard 10, by gearing (not shown) to the lower end of an inner feed-shaft 36 journaled in the frame-lug 12. At its upper end, within the belt-compartment 19, the feed-actuating shaft 35 is connected by a clip-belt 37 to the upper end of an outer feed-shaft 38 carrying at its lower end the feed-cup 14. The outer feed-shaft 38 is journaled in spaced bearings provided in the opposite ends of a station-

ary sheath 39 clamped at its upper end by a screw 40 in the split end 41 (Fig. 6) of a pivotally mounted feed-cup supporting element or lever 42. As shown in Figs. 2 and 5, the supporting lever 42 is mounted on alined fulcrum-studs 43 and 44. Fulcrum-stud 43 is preferably secured in the side wall of the overhanging bracket 11 and the fulcrum-stud 44 is secured in a bracket 45 fastened by two screws 46 on the bottom wall 47 of the overhanging bracket 11. Two separated fulcrum-studs are used in order to provide clearance for the clip-belt 37.

At the inner end of the feed-cup supporting lever 42 there is formed an offset lug 48 and at right angles to the main body of the supporting lever 42 a stop-arm 49 adapted to extend between two adjustable stop-bars 50 and 51, which limit the extent of movement of the outer feed-cup 14 toward and away from the inner feed-cup 13. It will be observed in Fig. 2 that the upper stop-bar 50 is threaded upon an adjusting screw 52 and is guided by a second adjusting screw 53, while the lower stop-bar 51 is threaded upon the second adjusting screw 53 and guided by the first adjusting screw 52. By having the upper stop-bar 50 adjustable, the outer feed-cup 14 may be initially set at various distances from the inner feed-cup 13 depending upon the thickness of the material being sewn. After the stop-bar 50 has been correctly set, the lower stop-bar 51 can be adjusted to limit movement of the outer feed-cup 14 in a direction away from the inner feed-cup 13. To facilitate assembly, the two adjusting screws 52 and 53 are reduced at their lower ends and set into apertures 54 drilled in the machine-frame, the screws 52 and 53 being maintained seated in these apertures 54 by the cover-plate 15 which rests upon flanges 55 formed upon the heads of the adjusting screws 52 and 53.

Referring to Fig. 1, it will be seen that the offset lug 48 at the inner end of the feed-cup supporting lever 42 is apertured to loosely receive the upper end of a square pull-rod 56 connected at its lower end, preferably by a chain 57, to a knee-control or foot-treadle (not shown). The pull-rod 56 is bodily movable endwise and rotatably mounted within a vertically disposed tubular housing or sheath 58 which projects downwardly through a hole in the partition 17 and, at its lower end, pressed into an upstanding boss 59 flanged, as at 60, for attachment on a raised seat 61 provided on the plate 20. A gasket 62 between the flange 60 and the seat 61 prevents the leakage of oil from the splash-lubrication compartment 18, as does the tubular housing 58.

Means is provided for yieldingly maintaining the outer feed-cup 14 in work-clamping relation with the inner feed-cup 13 and it is with this feature that the present invention is primarily concerned. To this end, there is provided a coil-spring 63 surrounding the upper portion of the pull-rod 56, the upper end of the spring 63 bearing against the bottom of the offset lug 48 on the feed-cup supporting lever 42 and the lower end of the spring bearing on a shouldered insert 64 carried at the top of a tubular spacer member 65 within the housing 58. The bottom of the spacer member 65 slides within the threaded bore 66 of the boss 59 and bears upon the top of a spring-pressure adjusting disk 67. To provide for locking the pressure-adjusting disk 67 in set position there is a second disk 68 separated from the disk 67 by a resilient washer 69, preferably made of an oil-resisting material such as neoprene, the resilient washer being under compression so that

it exerts a force tending to separate the two disks 67 and 68 and thereby increase the friction between the disks and the threaded bore 66 of the boss 59. Each of the disks 67 and 68 is formed with a centrally disposed aperture 70 shaped to correspond to the external shape of the pull-rod, but sized to permit free endwise sliding movement of the pull-rod relative to the disks 67 and 68.

As previously described, the upper end of the pull-rod 56 is loosely embraced by the apertured offset lug 48 of the feed-cup supporting lever 42, and to prevent rattling of the pull-rod against the offset lug there is provided a light compression spring 71 (Fig. 1) bearing at one end on the top of the offset lug 48 and at its other end against a nut 72 threaded on the upper end of the pull-rod 56. A spacing sleeve 73 surrounds the compression spring 71 to minimize the lost motion between the nut 72 and the offset lug 48 when the pull-rod 56 is actuated to separate the two feed-cups 13 and 14.

When it is required to regulate the pressure between the two feed-cups 13 and 14, it is necessary merely to insert a screw-driver through a clearance-opening 74 in the cover-plate 15 into the slot 75 provided in the upper end of the pull-rod 56 and turn the pull-rod. Turning of the pull-rod will cause the two disks 67 and 68 to travel as one up or down in the threaded bore of the boss 59 and in so doing will compress or release the spring 63. It will be appreciated that the square shape of the pull-rod and the corresponding square holes in the two disks 67 and 68 effectively key the disks to the pull-rod 56 so that turning of the rod will screw the disks up or down in the boss 59. While I have shown the pull-rod as having a square shape, it will be appreciated that the pull-rod can have any shape except round and will be effective in turning the disks as long as the hole in the disks are complementary to the external configuration of the pull-rod. It will be appreciated that the self-locking feature of the present invention is attained by virtue of the resilient washer 69 being under compression. The extent of compression of the washer 69 is controlled by withdrawing the pull-rod 56 and turning one of the disks 67, 68 relative to the other disk.

Fig. 7 illustrates a modification of the means employed for keying the spring-pressure adjusting disks 67 and 68 to the pull-rod 56. In the modification shown, it will be seen that the pull-rod 56 is round in cross-section and that it is provided with a transverse slot 75 preferably opening into its lower end. Projecting through the slot 75 is a diameter-bar 76 provided on the disk 67, the diameter-bar preferably being in the form of a pin pressed into alined holes drilled through the walls of the disk. It is obvious that with this construction the disks 67 and 68 are free to move lengthwise of the pull-rod 56 when the latter is turned about its longitudinal axis.

It will be understood that when a machine is equipped with the present invention the pressure between the feed-cups can be readily adjusted by merely turning the pull-rod 56 in the proper direction. The pull-rod is conveniently accessible to the operator through the clearance opening 74 in the cover-plate 15. The self-locking feature of the present invention is not only efficient, but functions automatically without any attention whatever from the operator after the proper initial compression of the resilient washer 69 is obtained.

Having thus set forth the nature of the invention, what I claim herein is:

1. A sewing machine having a frame, stitch-forming devices, opposed feed-cups for supporting and feeding material to said stitch-forming devices, a movable element supporting one of said feed-cups, a spring for biasing said movable element in one direction, and manually controlled connections for shifting said movable element against the action of said spring, said manually controlled connections including a bodily movable rotatably supported member accessible to the operator for regulating the pressure exerted by said spring.

2. A sewing machine having a frame, stitch-forming devices, opposed feed-cups for supporting and feeding material to said stitch-forming devices, a movable element supporting one of said feed-cups, a spring for biasing said movable element in one direction, and manually controlled connections for shifting said movable element against the action of said spring, said manually controlled connections including an endwise movable pull-rod supported for turning movement about its longitudinal axis, whereby manual turning of the pull-rod will regulate the pressure exerted by said spring.

3. A sewing machine having a frame, stitch-forming devices, opposed feed-cups for supporting and feeding material to said stitch-forming devices, a movable element supporting one of said feed-cups, a spring for biasing said movable element in one direction, and manually controlled connections for shifting said movable element against the action of said spring, said manually controlled connections including a bodily movable rotatably supported member for effecting a relative movement between the feed-cups and for regulating the pressure exerted by said spring, and locking means for preventing accidental rotation of said member.

4. A sewing machine having a frame, stitch-forming devices, opposed feed-cups for supporting and feeding material to said stitch-forming devices, a movable element supporting one of said feed-cups, a spring for biasing said movable element in one direction, and manually controlled connections for shifting said movable element against the action of said spring, said manually controlled connections including a bodily movable rotatably supported member accessible to the operator, and spring-engaging means operatively associated with said movable element for regulating the pressure exerted by the spring when said member is rotated.

5. A sewing machine having a frame, stitch-forming devices, opposed feed-cups for supporting and feeding material to said stitch-forming devices, a movable element supporting one of said feed-cups, a spring for biasing said movable element in one direction, and manually controlled connections for shifting said movable element against the action of said spring, said manually controlled connections including a bodily movable rotatably supported member accessible to the operator, and spring-engaging means including a threadedly supported element connected to said bodily movable member so that turning of said member will shift said element and thereby change the pressure exerted by said spring.

6. A sewing machine having a frame, stitch-forming devices, opposed feed-cups for supporting and feeding material to said stitch-forming

devices, a movable element supporting one of said feed-cups, a spring for biasing said movable element in one direction, and manually controlled connections for shifting said movable element against the action of said spring, said manually controlled connections including an endwise movable pull-rod supported for turning movement about its longitudinal axis, spring-engaging means including a pair of disks threadedly supported in said frame and operatively associated with said pull-rod so that turning of the pull-rod will cause said disk to shift in a direction to compress or release said spring, and a resilient washer compressed between said disks.

15 7. A sewing machine having a frame, stitch-forming devices, opposed feed-cups for supporting and feeding material to said stitch-forming devices, a movable element supporting one of said feed-cups, a spring for biasing said movable element in one direction, and manually controlled connections for shifting said movable element against the action of said spring, said manually controlled connections including an endwise movable rotatably supported pull-rod having an out-of-round cross-section, and spring engaging means including a disk threadedly supported in said frame and apertured to conform to the external shape of said pull-rod, whereby said pull-rod can slide through said disk and said disk will be turned in said frame to compress or release said spring when the pull-rod is rotated about its longitudinal axis.

8. A sewing machine having a frame provided with an apertured internally threaded boss, stitch-forming devices, opposed feed-cups for supporting and feeding material past said stitch-forming devices, a movable element supporting one of said feed-cups, a spring for biasing said movable element in one direction, manually controlled connections for shifting said movable element against the action of said spring, said connections including an endwise movable rotatably supported pull-rod having at least a portion thereof substantially square in cross-section, and spring-pressure regulating means including a pair of disks threaded into said boss and having in-line square apertures through which projects the square portion of said pull-rod, and disk-separating resilient means interposed between said disks to frictionally lock them against accidental turning relative to said boss.

9. A sewing machine having a frame provided with an apertured internally threaded boss, stitch-forming devices, opposed feed-cups for supporting and feeding material past said stitch-forming devices, a movable element supporting one of said feed-cups, a spring for biasing said movable element in one direction, manually controlled connections for shifting said movable element against the action of said spring, said connections including an endwise movable rotatably supported pull-rod having a transverse slot formed in a portion thereof, and spring-pressure regulating means including a disk threaded into said boss and apertured to receive the pull-rod, and a diameter-bar provided on said disk and extending through the slot in said pull-rod, whereby rotation of said pull-rod will effect a shift of said disk relative to said boss.
